(57) **CLAIM**

The ornamental design for the label printer, as shown and described.

DESCRIPTION

The present design relates to a label printing device having a molded body, a flip-up edge support, a data entry means, a data view screen, a print button and a cut button.

FIG. 1 is a perspective view from above of the label printer of the present design.

FIG. 2 is a rear elevation view of the label printer of the present design.

FIG. 3 is a right side elevation view of the label printer of the present design.

FIG. 4 is a top plan view of the label printer of the present design.

FIG. 5 is a left side elevation view of the label printer of the present design.

FIG. 6 is a top plan view of the label printer of the present design; and,

FIG. 7 is a bottom plan view of the label printer of the present design.
